UNITED STATES PATENT OFFICE.

FAY HUNT, OF NEW YORK, N. Y.

DERRICK.

Application filed February 21, 1925. Serial No. 10,912.

To all whom it may concern:

Be it known that I, FAY HUNT, a citizen of the United States of America, and a resident of the city of New York, borough of the Bronx, in the county of Bronx and State of New York, have invented a new and Improved Derrick, of which the following is a description.

My invention relates to a derrick and particularly to a derrick having sills supporting the mast at the convergent ends of the sills and having braces known as stiff legs extending at the outer ends of the sills to the top of the mast.

The general object of my invention is to provide a derrick having increased flexibility and adaptability of adjustment with respect to the relative positions of the sills, the connection of the sills with the stiff legs and the connection of the stiff legs with the mast.

The nature of my invention and its distinguishing features and advantages will clearly appear as the description proceeds.

Reference is to be had to the accompanying drawings forming a part of this specification, it being understood that the drawings are merely illustrative of one example of the invention.

Figure 1 is a side elevation of a derrick embodying my invention;

Figure 2 is a plan view of the sills and the mast supporting base and pintle plate at the convergent ends of the sills;

Figure 3 is a fragmentary plan view showing another adjustment of the sills relatively to the base and pintle plate;

Figure 4 is a fragmentary plan view showing means for connecting the stiff legs at their upper ends with the mast;

Figure 5 is a view similar to Figure 4 but showing a different adjustment of the stiff legs and their connecting means;

Figure 6 is a vertical section through the pintle plate and mast seat, the section being taken on the line 6—6, Figure 8;

Figure 7 is a horizontal section on the line 7—7, Figure 6;

Figure 8 is an end elevation of the assembled pintle and mast seat;

Figure 9 is an end view of the stiff leg hitch or connecting means between the lower end of a stiff leg and the outer end of a sill;

Figure 10 is an end view of the stiff leg hitch shown in Figure 9;

Figure 11 is a horizontal section on the line 11—11, Figure 9;

Figure 12 is a vertical section of the mast top fitting;

Figure 13 is a front elevation of the mast top fitting.

Figure 14 a section along line 14—14 of Figure 12.

In Figure 1 the numeral 15 indicates the mast; 16, the sills at right angles or approximately so to each other; 17, the stiff legs. The boom 18 shown in Figure 1 and appurtenances thereto form no part of the present invention.

At the convergent ends of the sills 16 is a base 19 presenting a vertical opening 20 at one end. The base 19 is shown as composed of two longitudinal members in contact as at 21 beyond the opening 20. On the base 19 is imposed the pintle plate 22 having as usual spaced depending flanges 23 accommodated in the opening 20, said flanges having holes 24 to receive a transverse bolt 25 (Figure 1). The provision of pintles on the plate 22 is in accordance with my invention. Four of these pintles 26 are employed in practice so that they may be used in pairs to connect the pintle plate 22 with the sills. The means effecting connection between the sills 16 and the pintles 26 is illustrated as in the form of a plate or strap or casting 27 provided on each sill and having a vertical hole to receive a pintle. The connection is completed through the medium of cotters 28 passed through holes 29 in the pintles. The plate 22 is formed in practice with the usual central boss 30 which receives depending nipple or thimble 31 on the under side of the mast seat 32, there being a back wall 33 rising adjacent to said seat 32. The depending nipple or thimble 31 fits over the boss 30 and the opposed seating faces 34 are oblique and also keys 35 are fitted in straight transverse slots 36 in thimble 31 and engaging beneath an undercut shoulder 37 on the boss 30 to prevent vertical displacement of the mast seat 32. It will be readily understood

that the flanges 23 form bearings for the pin of the sheaves about which the ropes run after passing downwardly through the boss 30 in the usual manner and no further showing of this is required.

Comparing Figures 2 and 3, it will be seen that the sills 16 in Figure 2 are on two of the pintles 26 and extend beyond one end of

the base 19, whereas in Figure 3 the sills are engaged with a different pair of pins 26 and extend beyond the opposite end of the base 19. The provision for thus variously 5 disposing the sills 16 relatively to the pintle plate 22 permits of the sills being variously positioned to suit the particular ground or available space where the derrick is to be erected, and at the same time to insure a 10 stability as well as flexibility in the structure.

Referring to the stiff leg hitch or means connecting the lower end of a stiff leg 17 with the adjacent sill 16, as shown in Figures 1 and 2 and Figures 9 to 11, a pillow block 38 is provided, forming a seat for a rockable bearing 39 rounded at its center and having trunnions 40 receiving a transverse bolt 41 on the lower end of each stiff leg 17. The stiff leg hitch is completed by a cap 42 disposed over the bearing 39 and the pillow block 38. The arrangement permits of the rockable bearing 39 and its trunnions 40 with bolt 41 having 20 a universal movement when the stiff legs 17 are shifted from the position shown in Figure 4 to the position shown in Figure 5 and makes unnecessary any shifting of the sills 16 because of the changed position of the 25 stiff legs.

In order that the stiff legs at their upper ends may accommodate themselves to any relative positions of the sills 16, the following means are provided: A cap 43 of each 30 leg receives a vertical bolt 44 which passes also through an arm or gooseneck 45 to effect pivotal connection between said arm and the stiff leg. The gooseneck 45 pertaining to the respective stiff legs 17 are 35 both turnably engaged with a gudgeon pin 46 provided at the top of the mast 15. Said gudgeon pin 46 is disposed alongside a cap 47 on the mast 15. The gudgeon pin 46 has a transverse notch 48 near the lower end 40 which receives a rib or bead 48 on the cap 47, said rib being disposed between two vertical ribs 49 on said cap 47. The gudgeon 46 is clamped in position placed between the ribs 49 by U-bolts 50, the half round fitting 51 which receives the transverse pin 52 of the usual shackle for securing to the mast the topping lift tackle chain 53. The goosenecks 45 are secured to the caps or 50 fittings 43 on the respective stiff legs 17 by means of bolts 44, passing through the goosenecks 45 and vertically through said caps 43. Said goosenecks 45 are free to turn both 55 about the bolts 44 and about the gudgeon pin 46 on the mast so that the stiff legs 17 may take the position shown in Figure 4 or that shown in Figure 5. To secure the goosenecks 45 against turning for maintaining the stiff legs 17 in fixed position, bolts 53 are employed adapted to pass through a bolt 60 hole in the goosenecks 45 and through bolt 65 holes 54 in the caps 43. To limit the lateral swinging movement of the goosenecks 45 about the bolts 44, stop lugs 55 are provided on the caps 43 and each presents an oblique face toward the goosenecks 45 to 70 arrest said goosenecks at the proper angle.

With the described connection between the stiff legs 17 and the mast stop, I provide for a materially increased amplitude of swinging movement for the boom 18 since with the 75 stiff legs in the position shown in Figure 5, the boom may swing close against either gooseneck. This is so because the position of the gudgeon pin 46 which instead of passing through the stiff legs directly at 80 their juncture, is offset and remote from the convergent ends of the stiff legs.

I would state furthermore that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. In a derrick, sills at an angle to each other, means to support a mast adjacent the convergent ends of the sills, and pintles adjacent the convergent ends of the sills and disposed in pairs to permit of engaging the sills with various ones of the pintles for disposing the sills in various positions about the mast supporting means.

2. In a derrick, a pair of sills disposed at an angle to each other, a base adjacent the convergent ends of the sills, a pintle plate supported on said base and held thereto and presenting pins in various positions about 105 the center of the plate, said sills adapted to engage the different pins to variously dispose the sills about the pintle plate.

3. In a derrick, a pair of sills disposed at an angle to each other, a base adjacent the 110 convergent ends of the sills, a pintle plate supported on said base and held thereto and presenting pins in various positions, said sills adapted to engage the different pins to variously dispose the sills about the pintle 115 plate; together with a mast seat supported on said pintle plate.

4. In a derrick, stiff legs, sills, pillow blocks on the sills near their outer ends, and rockable members resting on said pillow blocks and secured to the stiff legs.

5. In a derrick, a mast, a cap on said mast, a rib on a face of said cap, a gudgeon pin having a notch adapted to receive said rib, stiff legs, and goosenecks pivotally connected with the gudgeon pin and the stiff legs.

6. In a derrick, a mast, stiff legs, fittings on said stiff legs at the top, goosenecks pivotally connected with said fittings, stops on the fittings limiting the lateral movement of 120

the goosenecks relatively to the stiff legs, and means to pivotally connect the goosenecks with the mast top.

7. In a derrick, a mast, stiff legs, fittings on said stiff legs at the top, goosenecks, means pivotally securing the goosenecks to the fittings, means to hold the goosenecks against pivotal movement, and means pivotally connecting the goosenecks with the

10 mast top.

8. In a derrick, a mast, a cap on said mast, a rib on a face of said cap, a vertical gudgeon pin having a notch into which said rib enters, a fitting coacting with said face of said cap and with said rib to clamp said 15 gudgeon pin in position, said fitting adapted to receive the connection with the usual topping lift tackle.

FAY HUNT.
